HOLDER FOR NUTS AND BOLTS

George S. Pratt, Glenolden, Pa.

Application February 8, 1956, Serial No. 564,192

6 Claims. (Cl. 211—133)

The present invention relates to a holder for nuts, bolts, washers and the like, and more particularly for a holder which may be clamped or otherwise secured to a work bench and which presents varying sizes of nuts, bolts, washers and the like to the user of the bench, either at the site of the holder or away therefrom.

In recent years there has been a considerable expansion of home workshops, so that carpentry, home repairs, and the like are being performed by far greater numbers of persons than in the past. Furthermore, rapid industrial mechanization and the adoption in many homes, shops, small plants and factories of a wide variety of equipment, has led to the necessity of having available at one location a large variety of fasteners, such as nuts, bolts, washers and other small implements of graduated size. For rapid utility to be made of any holder for such implements, it is necessary that such implements be readily withdrawn according to their size at the user's selection, and that when large amounts of such implements are needed, they may be readily transported away in their original container.

In the past, a variety of shelves, screw-cap jars, and the like have been devised in order to accomplish the storage of small implements. However, such prior devices have suffered from a number of serious handicaps. Thus, the use of shelves is very wasteful of space. Furthermore, shelving cannot be adequately associated with a work bench which is located away from the walls of a room. The use of screw-cap containers leads to lengthy manipulations in order to remove a small number of implements, such lengthy manipulations being required both to effect the removal of the screw-capped container and its subsequent reinsertion.

This invention has as an object the provision of a holder for varying sizes of implements which will permit selective withdrawal of such implements therefrom.

This invention has as a further object the provision of a holder comprising a plurality of containers, each of which may be separately manipulated to a position from which implements may be withdrawn therefrom, and each of which may be removed selectively from the holder, so that its entire contents may be transported to another location.

This invention has as yet another object the provision of a holder for varying sizes of small implements, which holder can be easily mounted in position adjacent to or affixed to a work bench or the like.

For the purpose of illustrating the invention there is shown in the drawings a form which is presently preferred; it being understood, however, that this invention is not limited to the precise arrangements and instrumentalities shown.

Figure 1 is an elevational view of one embodiment of the present invention.

Figure 2 is a plan view of the embodiment shown in Figure 1.

Figure 3 is a sectional view on line 3—3 of Figure 2.

2

Figure 4 is a plan view from below of a bracket-container component of the present invention taken on line 4—4 of Figure 3.

Figure 5 is an exploded view of a bracket-container component of the present invention.

Referring to the drawings, the holder of the present invention is designated generally by the numeral 10 and comprises an elongated integral cylindrical rod 12 having a plurality of evenly spaced slots 14 of annular cross-section disposed along its axis, the various slots 14 being joined together by an interconnecting core 16.

The rod 12 is anchored to workbench 15 by means of flange 17 provided with a set screw 19.

As shown particularly in Figure 1 the interconnecting core 16 of rod 12 has a uniform diameter throughout its length and extends through each of slots 14 at the centermost portion thereof.

Holder 10 is provided with a plurality of brackets 18, each of which is preferably formed from angled sheet metal. Each bracket 18 includes an elongated flat portion 20 and an upright end portion 22. The end of flat portion 20 remote from upright end portion 22 is provided with a generally V-shaped notch 24. The mouth of notch 24 is preferably wider than the diameter of core 16, while the width of the base 28 of notch 24 is generally less than the diameter of core 16.

A cup-shaped container 30, preferably made of transparent plastic, such as methyl methacrylate is fixedly secured as by a basal anchorage machine screw 32 and nut 33 to the upper surface of flat portion 20.

It will be noted, particularly in Figure 3 that the axial height of each of slots 14 is but slightly greater than the thickness of flat portion 20, so that flat portion 20 may be inserted by means of notch 24 into the slots 14 of rod 12. When so inserted bracket 18 is retained in position when core 16 is wedged into notch 24.

The use of holder 10 is as follows:

A plurality of brackets 18 are vertically mounted on rod 12 with their containers 30 disposed one above the other. Preferably, each container 30 should contain implements of a given size, with the gradations in size from implement to implement increasing with each lower container 30.

When the user of the workbench 15 desires to remove a few of the implements from one of the containers 30, he can readily obtain access to the desired container 30 by rotating its bracket 18, as by digital pressure on the upright end portion 22 thereof, out of phase with the remaining brackets 18 on rod 12.

Should the user of the workbench 15 desire to remove a substantial number or all of the implements within a given container 30 and transport them to an area distant from holder 10, this may be readily accomplished by withdrawing the bracket 18 from holder 10, as by the exertion of pressure on upright end portion 22 along a radial plane away from rod 12. The bracket 18 and its container 30 may be returned to rod 12 when the user has satisfied his requirements from the contents of container 30.

The holder 10 of the present invention permits optimum use to be made of the edge portions of a workbench, and a plurality of such holders may be spaced adjacent a given edge or edges of a workbench to achieve satisfactory storage and classification of a large number of varying size implements.

The present invention may be embodied in other specific forms without departing from the spirit or essential attributes thereof and, accordingly, reference should be made to the appended claims, rather than to the foregoing specification as indicating the scope of the invention.

I claim:

1. A holder for varying sizes of nuts, bolts, washers, and the like, including an elongated rod, a plurality of axially spaced slots on said rod, each of said slots extending around the entire periphery of said rod with an inner core portion of the rod extending axially through the slots, a plurality of notched brackets rotatably and removably carried within said slots, with the notch of each of said brackets having a width at a point spaced from the mouth thereof somewhat less than the inner core portion of said rod, the notched portion of each bracket having a smaller thickness than the axial dimension of said slots, whereby the notched portion of said brackets can be inserted within said slots and frictionally grip the inner core portion of said rod so that said brackets may be rotated about said slotted rod, and an open-mouthed container fixedly secured upon each said bracket, with the height of said container being less than the axial spacing intermediate said slots.

2. A holder for varying sizes of nuts, bolts, washers, and the like, including an elongated cylindrical rod, a plurality of axially spaced annular slots on said rod, each of said slots extending around the entire periphery of said rod with an inner core portion of the rod extending axially through the slots, a plurality of notched brackets rotatably and removably carried within said slots, with the notch of each of said brackets having a width at a point spaced from the mouth thereof somewhat less than the inner core portion of said rod, the notched portion of each bracket having a smaller thickness than the axial dimension of said slots, whereby the notched portion of said brackets can be inserted within said slots and frictionally grip the inner core portion of said rod so that said brackets may be rotated about said slotted rod, and an open-mouthed container fixedly secured upon each said bracket, with the height of said container being less than the axial spacing intermediate said slots.

3. A holder for varying sizes of nuts, bolts, washers, and the like, including an elongated rod, a plurality of axially spaced slots on said rod, each of said slots extending around the entire periphery of said rod with an inner core portion of the rod extending axially through the slots, a plurality of notched brackets rotatably and removably carried within said slots, with the notch of each of said brackets having a width at a point spaced from the mouth thereof somewhat less than the inner core portion of said rod, and having a generally V-shaped configuration, the notched portion of each bracket having a smaller thickness than the axial dimension of said slots, whereby the notched portion of said brackets can be inserted within said slots and frictionally grip the inner core portion of said rod so that said brackets may be rotated about said slotted rod, and an open-mouthed container fixedly secured upon each said bracket, with the height of said container being less than the axial spacing intermediate said slots.

4. A holder for varying sizes of nuts, bolts, washers, and the like, including an elongated cylindrical rod, a plurality of axially spaced annular slots on said rod, each of said slots extending around the entire periphery of said rod with an inner core portion of the rod extending axially through the slots, a plurality of notched brackets rotatably and removably carried within said slots, with the notch of each of said brackets having a width at a point spaced from the mouth thereof somewhat less than the inner core portion of said rod, and having a generally V-shaped configuration, the notched portion of each bracket having a smaller thickness than the axial dimension of said slots, whereby the notched portion of

said brackets can be inserted within said slots and frictionally grip the inner core portion of said rod so that said brackets may be rotated about said slotted rod, and an open-mouthed transparent cup-shaped container fixedly secured upon each said bracket, with the height of said container being less than the axial spacing intermediate said slots.

5. A holder for varying sizes of nuts, bolts, washers, and the like, including an elongated rod, a plurality of axially spaced slots on said rod, each of said slots extending around the entire periphery of said rod with an inner core portion of the rod extending axially through the slots, a plurality of notched brackets rotatably and removably carried within said slots, with the notch of each of said brackets having a width at a point spaced from the mouth thereof somewhat less than the inner core portion of said rod, the notched portion of each bracket having a smaller thickness than the axial dimension of said slots, whereby the notched portion of said brackets can be inserted within said slots and frictionally grip the inner core portion of said rod so that said brackets may be rotated about said slotted rod, and an open-mouthed container fixedly secured upon each said bracket at a spaced distance from the notched end of its bracket, said bracket portion intermediate the notched end and said container being planar and of sufficient length to serve as a ladle-handle for said open-mouthed container when said bracket-and-container are removed from engagement with said rod, with the height of each container being less than the axial spacing intermediate said slots.

6. A holder for varying sizes of nuts, bolts, washers, and the like, including an elongated cylindrical rod, a plurality of axially spaced annular slots on said rod, each of said slots extending around the entire periphery of said rod with an inner core portion of the rod extending axially through the slots, a plurality of notched brackets rotatably and removably carried within said slots, with the notch of each of said brackets having a width at a point spaced from the mouth thereof somewhat less than the inner core portion of said rod, and having a generally V-shaped configuration, the notched portion of each bracket having a smaller thickness than the axial dimension of said slots, whereby the notched portion of said brackets can be inserted within said slots and frictionally grip the inner core portion of said rod so that said brackets may be rotated about said slotted rod, and an open-mouthed cup-shaped container fixedly secured upon each said bracket at a spaced distance from the notched end of its bracket, said bracket portion intermediate the notched end and said container being planar and of sufficient length to serve as a ladle-handle for said open-mouthed cup-shaped container when said bracket-and-container are removed from engagement with said rod, with the height of said container being less than the axial spacing intermediate said slots.
